SILENCER

Leino H. Bille, St. Paul, Minn., assignor to Donaldson Company, Inc., St. Paul, Minn., a corporation of Delaware

Application July 15, 1955, Serial No. 522,292

1 Claim. (Cl. 181—54)

My invention relates generally to improvements in a silencer for a gaseous medium. It has been found particularly useful in silencing the exhaust gases of internal combustion engines; and it is in particular a silencing device of the type generally known as mufflers.

The gaseous medium discharged from the exhaust of internal combustion engines is subject to pressure pulsations which produce very objectionable noises unless attenuated or silenced in some manner before the gaseous medium is discharged to atmosphere. Mufflers are inserted in the exhaust conduits of such engines to accomplish attenuation or effective silencing of the exhaust gases and this is their primary function. As more and more vehicles such as automobiles, buses and trucks are being used today, particularly in city areas, so that there is a great deal of congested vehicle traffic, it becomes essential that a maximum degree of silencing of the exhaust gases from these vehicles is effected.

A principal object of my invention is to provide a novel and improved silencer or muffler construction which produces more effective attenuation or effective silencing of the exhaust gases than mufflers now known; and yet provide a muffler which is of simple design and construction.

Generally, exhaust mufflers for a vehicle are constructed with an end outlet which is coupled to and opens axially rearwardly into an elongated, axially extending member, commonly referred to as a tail pipe.

Further objectives of my invention are to provide a novel and improved silencer or muffler construction having a side outlet and which:

- (1) Diverts and disperses the exhaust gases and sound sideways and down underneath the vehicle chassis;
- (2) Permits the length of the muffler to be held to a minimum due to elimination of the end outlet;
- (3) Keeps exhaust heat away from the right rear tire and air brake diaphragm chamber; and
- (4) Eliminates the tail pipe customarily coupled to a muffler.

The above and other objectives and advantages of my invention will become apparent from the following specification and claims, reference being had to the accompanying drawings wherein:

Fig. 1 is a view in axial section of my invention; and Fig. 2 is a view partly in vertical section and partly in elevation taken on the line 2—2 of Fig. 1.

Referring more particularly to the drawings, wherein like parts will be indicated by the same numerals, my invention comprises an elongated tubular housing or outer shell 10 having opposite end walls 11 and 12. Longitudinally spaced transverse partitions 13, together with end walls 11 and 12, divide the interior of housing 10 into a plurality of longitudinally aligned chambers, indicated by the numerals 14—21. One of the intermediate chambers, and specifically chamber 19, has an outlet therefrom; and chamber 19 is defined as an outlet chamber. The remaining chambers are closed chambers; and

2

of these, chamber 14 is defined as the front end chamber and chamber 21 is defined as the rear-end chamber.

I provide an elongated exhaust conduit means, indicated generally by the numeral 22, which is preferably made up primarily of tubular sections 23, 24, 25 and 26. Section 23 forms an inlet end 27 of conduit means 22. Inlet end 27 opens axially outwardly in axially outwardly spaced relation to end wall 11; and section 23 projects from inlet end 27 through end wall 11 axially into the housing 10 to terminate at its opposite open end in one of the intermediate chambers. Specifically section 23 extends completely through front end chamber 14 and extends into intermediate closed chamber 15. Tubular section 24 extends from intermediate chamber 15 completely through intermediate chamber 16 into chamber 17. Section 24 is in offset, generally laterally spaced parallel relationship with section 23 so that adjacent ends of sections 23 and 24 which extend into the same closed chamber 15 provide what is known as an S gap therebetween. Section 25 extends from intermediate chamber 17 to terminate in rear end chamber 21, and is in longitudinally spaced generally axially aligned relationship with section 23; wherein the adjacent ends of sections 24 and 25 in the common intermediate chamber 17 are spaced and offset to provide a similar S gap. Tubular section 26 is disposed in laterally spaced generally parallel relationship to section 25 and extends from rear end chamber 21 through intermediate chamber 20 to terminate adjacent the partition 13 dividing chambers 19 and 20 with its end opening into outlet chamber 19. The adjacent open ends of sections 25 and 26 in rear end chamber 21 provide a C gap therebetween. The direction of flow through the silencer or muffler is indicated by flow arrows on Fig. 1; and it will be understood that the inlet end 27 is adapted to be coupled in or formed as an integral part of the exhaust pipe of an engine's exhaust system. As the flow arrows indicate, conduit means 22 defines an exhaust passageway from inlet end 27 axially through the housing 10 to rear end chamber 21 and then in the opposite direction from rear end chamber 21 back to outlet chamber 19.

Housing 10 has a lateral opening 28 formed in its side wall which communicates with outlet chamber 19 to provide an outlet therefrom. I provide a laterally outwardly projecting rearwardly opening snout, indicated generally by the reference numeral 29, which is anchored to housing 10 adjacent the lateral opening 28 and in communication with outlet chamber 19 through opening 28. Preferably, snout 29 projects through opening 28 and adjoins housing 10 about the periphery of opening 28 and is rigidly anchored to housing 10 at such adjoining points by welding or the like. Preferably, snout 29 is elbow-like and defines a passageway having an inlet 30 opening laterally inwardly into outlet chamber 19 and having a generally rearwardly opening discharge aperture 31 leading to atmosphere laterally outwardly of housing 10. Snout 29 comprises an arcuate front wall 32 extending between the inlet opening 30 and the discharge aperture 31 thereof, and a pair of laterally spaced parallel generally flat side walls 33, each of generally pie-shaped form. Arcuate front wall 32 acts to smoothly direct the gaseous medium through snout 29 from outlet chamber 19 to discharge rearwardly to atmosphere. Side walls 33 are preferably formed integrally with arcuate front wall 32.

That portion of conduit means 22 between rear end chamber 21 and inlet end 27 which is enclosed within outlet chamber 19, which is that portion of that section 25 indicated by the numeral 34, is imperforate; however, the remaining portions of sections 23, 24, 25 and 26 of conduit means 22 are provided with a plurality of passages leading through the walls thereof into the adjoining closed

chambers, which define resonance or attenuating chambers. The passages are preferably arranged in a multiple perforation pattern similar to that described and claimed in my co-pending application, Serial Number 439,670 filed on June 28, 1954.

The construction of my novel and improved muffler with snout 29 providing an exhaust outlet from an intermediate outlet chamber permits the length of the muffler to be held down to a minimum and it eliminates the customarily used tail pipe, generally extending rearwardly beyond the ordinary muffler construction. The tail pipe of the ordinary muffler construction is often in need of repair and replacements so that its elimination is very advantageous. My muffler construction is adapted to be connected in the exhaust conduit of an internal combustion engine of a vehicle so that snout 29 diverts and disperses the exhaust gases and sound sideways and down underneath the vehicle chassis which aids in effecting the attenuation of the sound or noise. Further, the positioning of my muffler keeps exhaust heat away from the right rear tire and air brake diaphragm chamber which is not true of muffler constructions now generally known.

It is clear that the specific construction of the exhaust conduit means 22 shown in the drawings, which is basically of the type characterized as a "2S gap" extended range muffler, is not required, but it may be modified in many respects. For example, exhaust conduit means 22 between its inlet end 27 and rear end chamber 21 might comprise a single straight through section or longitudinally spaced sections providing a straight gap rather than an S gap. Further, communication between sections 25 and 26 of conduit means 22 might be accomplished by a C shaped connecting section or the like, instead of the C gap shown in Fig. 1. In addition, it is clear that the number of chambers formed in housing 10 is not critical but may be varied in many respects. It will be obvious to those skilled in the art that my invention may be modified by many substitutions and equivalents and that this disclosure is intended to be illustrative only; therefore, I

intend to be limited solely by the scope of the appended claim.

What I claim is:

5 In a silencer for a gaseous medium, an elongated housing having opposite end walls, transverse partition means dividing the interior of said housing into front and rear end chambers and intermediate chambers, one of said intermediate chambers defining an outlet chamber, said housing having a lateral opening through its side wall providing an outlet from said outlet chamber, a laterally outwardly projecting elbow-like snout anchored to said housing adjacent said lateral opening and defining a discharge passageway opening laterally inwardly at one end into said outlet chamber and having a generally rearwardly opening 10 discharge aperture to atmosphere, and an elongated exhaust conduit means having an inlet end extending through the housing end wall adjoining the front end chamber, said conduit means extending axially within said housing through said partition means from said inlet end to said 15 rear end chamber and from said rear end chamber to said outlet chamber and terminating in an opening into said outlet chamber, that portion of said conduit means between said rear end chamber and the inlet end thereof which is enclosed within said outlet chamber being imperforate and 20 other portions of said conduit means being provided with a plurality of passages leading through the walls thereof into said chambers.
